UNITED STATES PATENT OFFICE.

THOMAS H. BUCKLEY, OF WORCESTER, MASSACHUSETTS.

DESIGN FOR A LUNCH-WAGON BODY.

SPECIFICATION forming part of Design No. 33,515, dated November 6, 1900.

Application filed June 28, 1900. Serial No. 21,998. Term of patent 14 years.

To all whom it may concern:

Be it known that I, THOMAS H. BUCKLEY, a citizen of the United States, residing at Worcester, in the county of Worcester and 5 State of Massachusetts, have invented and produced a new and original Design for a Lunch-Wagon Body, of which the following is a specification, reference being had to the accompanying drawings, forming a part 10 thereof.

My invention relates to a lunch-wagon body; and it consists in a new and original design for a lunch-wagon body, as will be hereinafter fully described.

15 Referring to the drawings, Figure 1 is a perspective front end view of a lunch-wagon body, showing my design; and Fig. 2 is a perspective rear end view of a lunch-wagon body, showing my design.

20 In the accompanying drawings, the wagon-body has the solid lower or base portion 1 extending around the two ends and one side of the body and for about half the height of the body. The other side of the body has the

25 solid portion broken and divided by a doorway and door 2, extending nearly the full

height of the body 1, as shown in Fig. 1. There is also on this same side a window or panel 3 in the solid portion 1 of the body near one end of the wagon-body. 30

Above the solid portion 1 of the body and extending around the body, except where the door 2 appears and the panels to be herein-after referred to, are a series of plain windows of substantially uniform size and shape 35 and forming the upper portion of the body of the wagon.

On the side of the body of the wagon where the door 2 appears are two solid panels 5 5—a panel between each pair of windows on 40 each side of the door 2. On the opposite side of the wagon-body there are four solid panels 6, arranged alternately with the windows, except at one end, where there are two contiguous windows. 45

What I claim is—

The design for a lunch-wagon body, substantially as shown and described.

THOMAS H. BUCKLEY.
